SUSPENSION FOLDER

Robert Kelley, Ogdensburg, N.Y., assignor to Natser Corporation, doing business as Acco Products, Ogdensburg, N.Y., a corporation of Nevada

Filed Aug. 6, 1964, Ser. No. 81,187

Term of patent 14 years

(Cl. D74—2)

FIG. 1 is a perspective view of a suspension folder showing my new design;

FIG. 2 is an enlarged elevational view of one side thereof;

FIG. 3 is an elevational view of the other side thereof; and

FIG. 4 is an end elevational view thereof.

I claim:

The ornamental design for a suspension folder, substantially as shown.
